UNITED STATES PATENT OFFICE.

HARRY F. JOSEPH, OF DAVENPORT, IOWA, ASSIGNOR OF ONE-HALF TO HENRY P. JOHANSEN, OF DAVENPORT, IOWA.

FLOOR-CLEANSING APPARATUS.

1,149,835.

Specification of Letters Patent. Patented Aug. 10, 1915.

Application filed January 17, 1914. Serial No. 812,744.

To all whom it may concern:

Be it known that I, HARRY F. JOSEPH, citizen of the United States, residing at Davenport, in the county of Scott and State 5 of Iowa, have invented certain new and useful Improvements in Floor-Cleansing Apparatus, of which the following is a specification, reference being had to the accompanying drawings.

10 This invention relates to scrubbing machines and is designed with the primary object in view of providing a machine which is capable of thoroughly and rapidly scrubbing and drying a large floor space such for 15 instance, as those usually found in halls and other large auditoriums.

The invention has for a further object to provide a machine for the above purpose including a plurality of oscillating scrubbing brushes, water supply means for the brushes carried by the machine, a mop operating in the rear of the brushes to dry the floor, and means automatically actuated from the handle bars of the machine by 25 which it is propelled to engage or disengage the brushes with or from the floor surface and simultaneously lower or raise the mop to its operative or inoperative position.

The invention has for a more particular 30 object to provide simple, novel and effective means for imparting a rotary oscillating movement to the scrubbing brushes as the machine is moved over the floor.

The invention further contemplates the 35 provision of a mopping device including an endless mopping cloth or web, operating means for said web removably mounted in the main frame of the machine and including a roller having frictional engagement 40 with the floor surface, means controlled from the handle bars for yieldingly holding the lower stretch of the mopping web in engagement with the floor surface, and additional means operable when the handle bars 45 are released to elevate the mop and its frame out of co-operative relation with said friction roller.

The invention has for still another object 50 to provide novel means whereby the endless mop may be easily and quickly removed and a new one placed in position when necessary.

A further object of the invention resides in the provision of water supply means for the scrubbing brushes including a tank and hose extending therefrom to the brushes, cut 55 off valves to control the water supply, and connections between the valves and the handles of the machine whereby pressure against the handle to propel the machine opens the valves and the release of said handles 60 automatically closes said valves and cuts off the water supply.

The invention has for still another object to generally improve the construction of machines of the above character whereby their 65 utility and serviceability in actual use is greatly enhanced without complicating the construction to any material extent or increasing the manufacturing cost.

With the above and other objects in view 70 as will become apparent as the description proceeds, the invention consists in certain constructions, combinations and arrangements of the parts that I shall hereinafter 75 describe and claim.

For a full understanding of the invention, reference is to be had to the following description and accompanying drawings, in which—

Figure 1 is a side elevation of a combined 80 scrubbing and mopping machine constructed in accordance with the preferred embodiment of the invention; Fig. 2 is a similar view illustrating the inoperative positions of the scrubbing brushes and mop when the 85 handle bars of the machine are released; the brushes being shown in their elevated positions in dotted lines; Fig. 3 is a top plan view; Fig. 4 is a section taken on the line 4—4 of Fig. 3; Fig. 5 is a section taken on 90 the line 5—5 of Fig. 3; Fig. 6 is a section taken on the line 6—6 of Fig. 1; Fig. 7 is a section taken on the line 7—7 of Fig. 1; Fig. 8 is a section taken on the line 8—8 of Fig. 1; Fig. 9 is a section taken on the line 95 9—9 of Fig. 2; Fig. 10 is a section taken on the line 10—10 of Fig. 3; Fig. 11 is a section taken on the line 11—11 of Fig. 2; Fig. 12 is a section taken on the line 12—12 of Fig. 1; Fig. 13 is an enlarged fragmentary elevation illustrating the arrangement of the lifting roller; Fig. 14 is a detail section taken

on the line 14—14 of Fig. 4; Fig. 15 is a section taken on the line 15—15 of Fig. 9.

Referring in detail to the drawings, 5 designates the two similar side members of the main frame which includes the obliquely disposed bars 6, the plates 7 secured upon the forward ends of said bars and the bearing members 8 which are secured to the rear ends of the bars 6. These bearing members are loosely mounted upon the shaft 9 upon which the tank or reservoir 10 is secured, provision being made in the construction of the tank for the accommodation of the drive wheel 11 centrally journaled upon the shaft 9. The main frame of the machine further includes a substantially U shaped bar 12, the ends of which extend rearwardly and are provided with suitable bearings 13 for the ends of the shaft 9. To the arms of this U shaped frame, the handle bars indicated at 14 are connected, the lower ends of said bars being connected by a transverse brace bar.

The plates 7 on the forward ends of the frame bars 6 are connected by the transversely disposed rod or shaft 15 and upon the same, the rear curved ends of the longitudinally extending bars 16 are loosely mounted. These bars extend forwardly in parallel relation and upon their forward ends, the bearing members 17 are secured. In these bearing members, the vertical axles 18 of the rotary oscillating brushes generally indicated by the numeral 19 are mounted. Each of these brushes includes a body 20 preferably constructed of wood to which the axle 18 is centrally secured by means of a suitable screw or bolt 21. As illustrated in Fig. 3 of the drawings, the brush body 20 is of star-shaped form in plan and each of the radial extensions thereof is provided with a longitudinal groove or channel 22 into which a bar 23 in which the brush bristles 24 are fixed in any approved manner, is adapted to be inserted. These bars are securely held in the grooves of the brush body against longitudinal movement by means of the fastening screws 25. To the upper surface of the body 20 of each brush, a wear plate 26 is secured for engagement with the bearing member 17. The upper end of each brush axle 18 is provided with an arm 27 having a pin 28 formed upon its outer end. To this pin, the forward end of a lever 29 is loosely connected.

30 designates a support upon which link bars indicated at 31 are mounted, one of said link bars being arranged upon each side of the center of said support. Each of the links is formed with a thickened central portion having an elongated slot 32 therein. Within each of these slots a block 33 is disposed, said blocks being pivoted upon the support 30 by means of the vertical bolts or pins 34. The outer end of each of the link

bars 31 is pivotally connected to the rear end of one of the levers 29 while the inner ends of said link bars are similarly connected to the slide block 35 mounted between suitable guides 36 provided upon the support 30.

For purposes which will more fully appear from the following description, the support 30 is longitudinally adjustable upon the bars 16 and is secured in its adjusted position by suitable bolts indicated at 37. In order to compensate for unevenness in the floor surface and wear upon the bristles of the brushes, I provide upon the under side of the support 30, and centrally thereof, an annular interiorly threaded flange 38. A sleeve 39 is threaded in this annular flange, said sleeve being closed at one end and provided with a stud or pin 40 centrally thereof.

41 indicates the bearing for a wheel or caster 42, said bearing being provided with a hollow cylindrical body 43 to house a coiled spring 44 arranged upon the pin 40. This pin is adapted to project through the end wall of said housing between the arms of the bearing member 41 and is equipped with a suitable head 45. It will be understood from this construction, that the roller 42 is normally forced downwardly by the spring 44 into contact with the floor surface as the machine is propelled over the same. By simply adjusting the sleeve 39 within the threaded flange 38, the normal height at which the support 30 is disposed above the floor surface may be regulated as circumstances and wear upon the brush bristles may indicate to be necessary. The extent of rotary oscillating movement of the brushes 19 may be easily and quickly changed or varied as desired by simply adjusting the support 30 longitudinally upon the frame bars 16.

The connecting rod 46 has its forward end pivotally connected to the side block 35, and the rear end terminates in a hook 46' for engagement with the pin 47 mounted upon one end of a crank arm 48, said arm being suitably secured to one face of a pinion 49. The pin 47 is provided with a reduced screw threaded portion to receive a suitable nut 50 whereby the connecting rod 46 may be readily removed from the crank arm or connected thereto. The pinion 49 is suitably journaled upon the bearing support 12' carried by the U shaped frame member 12 and meshes with a similar pinion 51 also journaled upon said frame member. This latter pinion in turn engages the teeth of a gear wheel 52 which is bolted or otherwise secured to the drive wheel 11. It will be readily understood from the above description that in the movement of the machine over the floor, a reciprocating movement is transmitted to the connecting rod 46 through the medium of the crank arm 48, which rod in turn actuates the slide block 35.

35. As this block is actuated, the links 31 are moved together upon the pins 34, and the levers 29 connected to the crank arms 27 operate to impart a rotary oscillating movement in opposite directions to the brushes 19. By providing one of the links 31 in each pair with a slot for sliding movement upon the other link, a maximum movement of the levers 29 may be obtained with 10 a minimum sliding movement of the block 35. The brushes are so mounted that the arms of one brush move into the spaces between the arms of the other brush when the brushes are rotated. Thus every portion of 15 the floor surface over which the machine is moved will be engaged and scrubbed by the brush bristles.

Water is supplied to the brushes slightly in advance thereof by means of the flexible 20 hose indicated at 53 said hose being connected to the water supply tank or reservoir 10. Suitable valves indicated at 54 control the supply of water to the brushes and are automatically opened and closed by means 25 of the rods 54' which connect the arms 55 of the valve plugs with the U shaped bar 12 of the frame, in the manner which will be hereinafter more fully explained.

In conjunction with the scrubbing brushes, 30 I employ an endless traveling mop, the same being constructed and arranged in the following manner: Two similar frame plates 56 are employed in which the ends of a roller shaft 57 are journaled. Upon this shaft the 35 roller 58 constructed of wood is secured. Each of the frame plates 56 is provided with a laterally projecting stud 59 which is adapted to be received in a slot 60 provided in the upper edge of the frame plate 7.

40 In order to compensate for wear of the traveling mop, and to regulate the pressure of the same upon the floor surface, I provide the adjustable bearing elements indicated at 59' which are pivoted at one of 45 their ends as at 59a upon the plates 7. The other ends of these bearing members project inwardly and are provided with adjusting screws 59b which are adapted to bear upon the upper edges of the plates 7. It will 50 be noted that the members 59' are longitudinally curved and by adjusting the same, they may be raised or lowered with respect to the lower ends of the slots 60. Upon these adjustable bearings, the studs 59 of the mop 55 frame are supported.

Upon the forward lower portion of each of the plates 56, a rectangular metal housing or casing 61 is pivotally mounted at one of its ends as indicated at 61'. Within this casing 60 a rod 62 is movably mounted. This rod is provided with a reduced portion upon which a spring 64 is arranged within the casing, said spring at one of its ends bearing against the shoulder 63 formed upon 65 the rod by reducing the same and at its other

end against one of the end walls of the casing. A nut 65 is threaded upon the reduced end of said rod. The forward end of each of the rods 62 is notched as at 66 to provide bearings for the trunnions 67' upon the ends 70 of a roller 67. A spring held check rod 104 is also mounted upon each of the plates 56 said rods bearing upon the forward ends of the casing 61 and acting to force the roller 67 downwardly. 75

To the lower edge of each plate 56 and projecting inwardly therefrom, a spring clip 105 is secured, said clips extending beneath the forward ends of the casings or housings 61 and serving to support the same 80 when the forward ends of the frame plates are elevated in the manner to be later described.

68 designates an endless mop constructed of felt or any other desired material which 85 traverses the rollers 58 and 67. The lower stretch of this mop is disposed in a horizontal plane and is adapted for movement over the floor surface, said lower stretch of the mop moving forwardly, and tending to 90 carry the water collected in front of the mop upwardly and rearwardly where suitable means is provided which acts by compression to extract the water from the mop. This means includes a roller 69 which is 95 mounted at its ends in the metal blocks 70 (see Fig. 6). These blocks are provided with tongues 71 which are dove-tailed for sliding movement in the grooves 72 provided in the frame plates 56. This block is provided with an inwardly extending arm 73 for engagement with a trunnion on the end of the compressor roller 69.

Upon the body of the block a hollow member 74 is mounted, through which a rod 75 extends, said rod also extending through the arm 73 and having a nut 76 threaded upon its upper end. 105

A spring 77 is arranged within the hollow member 74 and bears against one end thereof, the other end of said spring engaging a suitable head formed in the lower end of the rod 75. It will be apparent that by simply adjusting the nuts 76, the tension of these springs and consequently the pressure of the roller 69 upon the web of the mop 68 110 may be regulated. 115

In order to disengage the bearing arms 73 of the blocks 70 from the trunnions of the roller 69, I provide the levers 78 which are fulcrumed at one of their ends upon the respective frame plates 56 as indicated at 79. To each of these levers, intermediate of its ends, one end of a link 80 is pivotally connected, the other ends of said links being loosely mounted upon the pins 81 formed upon the members 74 and having movement in the slots 82 provided in the frame plates 56. By simply moving the levers 78 in the proper direction, the bearing arms 73 of 120 125 130

the blocks 70 will be moved upwardly out of contact with the roller trunnions so that said roller may be removed. In order to position the mop 68 upon the rollers 58 and 67 or remove the same therefrom, the roller 67 is forced rearwardly against the action of the springs 64, and the endless mop web moved transversely of the machine over one of the frame plates 56. Upon the release of the roller 67, the springs 64 force the same outwardly and stretch the mop web or tightly engage the same upon the peripheries of the rollers 67 and 58.

A trough 83 is mounted between the frame plates 7 and is adapted to receive the water pressed from the traveling mop by the roller 69. This trough is suitably mounted at its ends upon the frame plates 56 and extends transversely between the upper and lower stretches of the mop 68. A tube or hose 83' is suitably connected to each end of said trough and extends rearwardly therefrom, the other open end of said tube being connected to or disposed above the pan 84 and discharging into the same. This pan is suitably hung or suspended from the water supply tank 10 and a tank 85 which is arranged upon the rear of the tank 10. The dirty water in the pan 84 is pumped into the tank 85 by means of a suitable pump indicated at 86 which is mounted upon the water tank or reservoir 85, said pump being operated by means of the eccentric 106 secured to the drive wheel 11.

In order to maintain the lower stretch of the traveling mop 68 in sliding contact with the floor surface, I provide the curved levers 87 fulcrumed as at 88 upon the frame plates 7. To the lower rear ends of these curved levers the rear ends of the coil springs 89 are suitably connected, the forward ends of said springs being equipped with the metal blocks 90 to which the rear ends of the hooks 91 are pivotally connected. These hooks are adapted for engagement with lugs 93 formed upon the rear ends of the arms 92 which are secured to the respective frame plates 56 upon and between which the traveling mop is mounted. Longitudinally disposed lever bars 94 are fulcrumed intermediate of their ends upon the depending brackets 95 secured or formed upon the arms of the U shaped bar 12. The rear ends of these levers are pivotally connected at 96 to the vertical handle bars 14. Upon the forward end of each of these levers, a roller 97 is mounted. These rollers are adapted for engagement with the rear curved edges 98 of the frame plates 56, and also bear against the forward ends of the curved levers 87. Upon each end of the shaft 57, a friction wheel 99 is secured, with which a similar wheel 100 mounted upon the shaft 15 is engaged. These latter wheels contact with the floor surface and by their frictional en-

gagement with the wheels 99 operate to rotate the roller 58 in the movement of the machine whereby the endless traveling mop 68 is operated. From this construction, it will be seen that when forward pressure is applied to the handle bars 14 to propel the machine over the floor, the frame 12 will be oscillated upon the shaft or axle 9 and the bristles of the rotary brushes 19, lowered into contact with the floor surface. The bars 94 will also be moved upon the hanger brackets 95 and the forward ends of said bars moved downwardly whereby the rollers 97 bearing against the forward ends of the levers 87 rock said levers upon their pivots and move the rear ends thereof rearwardly and upwardly, thereby expanding the springs 89. The contractile force of these springs exerts a rearward pull upon the mop frame and tends to rock the same in the supporting plates 7, thus holding the lower stretch of the traveling mop 68 down upon the floor surface in firm constant contact therewith during the movement of the machine. As soon as pressure against the handle bars 13 is released and said bars forced downwardly, the upward movement of the forward end of the U shaped frame bar 12 cuts off the supply of water to the brushes automatically and elevates the brushes through the medium of the connecting bar 46 to dispose the bristles out of contact with the floor surface. It will be understood that in the upward movement of the forward intermediate portion of the frame bar 12, the same engages the rod 46 so as to exert an upward pressure against the same and thus elevate the brushes to the position shown in full lines in Fig. 2. Simultaneously with this elevation of the brushes, the forward ends of the bars 94 are raised and the rollers 97 bearing against the frame plates 56 force said plates upwardly, the lugs 59 on said plates rocking in the slots 60 of the plates 7, and raising the lower stretch of the traveling mop 68 out of contact with the floor surface. In this elevated position of the mop, the spring clips 105 support the castings 61 and prevent downward movement of the roller 67 which would engage the lower stretch of the mop 68 with the floor surface. The rollers 97 are also moved upwardly along the forward ends of the levers 87, and the coil springs 89 contract so that the same offer no resistance to the rocking movement of the mop frame.

From the foregoing description, taken in connection with the accompanying drawings, it is believed that the construction and manner of operation of the several parts of my machine will be clearly understood. As above stated, in the forward movement of the machine over the floor, a rotary oscillating movement in opposite directions is imparted to the brushes 19 to which water 13

is continuously supplied during the forward movement of the machine. When the machine is pulled backwardly in moving the machine from place to place, the rearward and downward movement of the handles automatically shuts off the water supply and elevates the brushes out of contact with the floor in the manner above explained.

During the scrubbing operation, the lower stretch of the mop 68 is held in close engagement with the floor surface by the springs 89, which also operate to maintain the friction wheels 99 in frictional contact with the peripheries of the drive wheels 100. Thus the mop 68 is operated, the lower stretch thereof moving forwardly around the tensioning roller 69. For the purpose of directing the water after it leaves the brush bristles to the central portion of the forward end of the mop, I provide the rubber squeegees 101 which are secured in suitable metal holders 102 suitably mounted upon the longitudinal frame bars 16. These squeegees extend from opposite sides of the central portion of the mop forwardly to points adjacent the outer sides of the respective brushes 19. The squeegees 101 bear closely against the floor surface and direct the water to the center of the mop. As the endless mop 68 moves upwardly and rearwardly over the tensioning roller 67, the mop becomes saturated with the water which is carried rearwardly to the presser roller 69. This roller is yieldingly held in contact with the upper stretch of the mop at a point adjacent the periphery of the roller 68 and forwardly of the axis thereof, so that the mop webbing is compressed between the two rollers and the water thus extracted therefrom. This dirty water as before explained, collects in the pan 83 from which it is discharged into the pan 84 and finally conveyed to the tank 85 by the pump 86. It will be understood that if desired, the mop and its frame may be bodily removed from the main frame of the machine and employed independently of and subsequently to the scrubbing operation. As soon as pressure against the handles 13 is released and said handles forced downwardly, the mop frame is elevated slightly upon the main frame to elevate the lower stretch of the mop out of contact with the floor surface and disengage the peripheries of the wheels 99 from the friction drive wheels 100, thus breaking the driving connection and stopping the movement of the mop. I preferably provide a hook or latch member indicated at 103 which is mounted upon the water receiving tank 85 to hold the handles in their lowered position so that after the mopping operation, the machine may be freely moved over the floor without again placing the same in operation. When the machine is not in use, the brushes 19 may

be elevated, the rod 46 being disposed in a substantially vertical position, the hook 46' on the end of said rod being adapted to be disconnected from the crank arm 48 and engaged with the transverse rod 107, which is suitably secured to one section of the tank 10 rearwardly of the shaft or axle 9.

It will be appreciated that owing to the fact that the mop and the brushes are very compactly arranged, the same may be readily moved beneath articles of furniture and the entire floor surface scrubbed by the rotary brushes. These brushes may be easily and quickly removed from the forward ends of the frame bars 16 and when the bristles thereof become greatly worn, any one or more of the bars to which the bristles are affixed may be easily and quickly removed from the body of the brush and a new row of bristles supplied thereto.

The machine as a whole is comparatively light in weight, and may therefore be easily and quickly moved from place to place by the operator with a minimum of labor.

The several parts entering into the construction of the invention are all of simple form thereby rendering the machine comparatively inexpensive to manufacture, and highly durable in practical use. The parts may also be readily assembled or disassembled by the operator for the purpose of cleaning or repairing the same.

While I have shown and described the preferred construction and arrangement of the several parts employed, it is to be understood that the invention is susceptible of a great many modifications therein and I therefore reserve the privilege of resorting to all such legitimate alterations as may be fairly embodied within the spirit and scope of the appended claims.

Having thus described the invention, what is claimed is:

1. In a machine of the character described, a wheel supported frame, a mop frame and mop carried thereby mounted for bodily movement upon said wheel supported frame, means to elevate the mop frame and hold the lower stretch of the mop out of contact with the floor surface, and a movable element connected to the mop frame and actuated by said means when the mop frame is lowered, to hold the mop in engagement with the floor surface.

2. In a machine of the character described, a wheel supported frame, a mop frame fulcrumed upon said wheel supported frame, an endless traveling mop mounted in the mop frame, pivotally mounted bars engaging at one of their ends with the mop frame, a handle connected to the other ends of said bars whereby the bars may be moved to rock the mop frame upon the wheel supported frame and elevate the lower stretch of the mop out of contact with the floor

- surface, and means actuated by said pivoted bars upon a reverse movement of the handle to yieldably hold the lower stretch of the mop in contact with the floor surface.
5. 3. In a machine of the character described, a wheel supported water supply tank, a scrubbing brush arranged forwardly of said tank, a mop mounted for bodily vertical movement rearwardly of the brush, 10 means for supplying water from the tank to the brush having a cut off valve, a movably mounted handle for propelling the machine, means to press the mop against the floor, and means for holding the brush and mop in elevated positions coöperating with said last named means when the mop and brush are lowered to positively engage the mop with the floor, and additional means also connected to said handle and operated thereby to open the valve of the water supply means.
4. In a machine of the character described, a wheel supported water supply tank, a brush arranged forwardly of said tank, means for supplying water from the tank to said brush including a control valve, an endless traveling mop mounted between the brush and the supply tank, means for operating said mop during the movement 30 of the machine over the floor, a movably mounted handle, means connected to said handle to support the mop in an inoperative position and out of contact with the floor surface in one position of the handle, additional means rendered operative by said mop supporting means in the movement of the handle by pressure thereagainst whereby the mop is yieldingly held in constant sliding contact with the floor surface, and means 35 operated in the last named movement of the handle to open said water control valve and supply water from the tank to the brush.
5. In a machine of the character described, a scrubbing brush and a mop arranged rearwardly of the brush, said brush and mop being mounted for bodily vertical movement, a movable handle whereby the machine is propelled, independently acting 45 members connected to said handle to sustain the brush and mop respectively, in elevated positions, whereby when the handle is moved in one direction, the brush and mop are permitted to move downwardly into engagement with the floor, and additional means to effect a constant positive application of pressure by the mop upon the floor surface during the operation of the machine.
6. In a machine of the character described, a main wheel supported frame, a 50 mop vertically movable in said frame, a brush arranged in advance of said mop, a water supply tank, means for supplying water from the tank to the brush including a 55 control valve, a movably mounted handle,

connecting means between the handle and the control valve whereby pressure against the handle automatically opens said valve, additional means connected to said handle to support the mop in an elevated position 70 upon the machine frame and hold the same out of engagement with the floor surface, and means operated by said supporting means upon the application of pressure against the handle to propel the machine 75 whereby said mop is yieldingly held in close engagement with the floor surface during the operating movement of the machine.

7. In a machine of the character described, a wheel supported shaft, a water supply tank mounted upon said shaft, a forwardly extending frame loosely mounted upon the shaft, a vertically movable mop mounted in said frame, a scrubbing brush supported upon said frame and disposed in 80 advance of said mop, means for supplying water from the tank to the brush including a control valve, a movable handle mounted upon said shaft whereby the machine is propelled, means connected to the control 85 valve and actuated by pressure against the handle to open the valve and supply water to the brush, means connected to said handle to support the mop in an elevated position in the machine frame out of contact with 90 the floor surface and also elevate the forward end of said frame to hold the brush out of engagement with the floor, and additional means actuated by said supporting means upon the application of pressure to 95 the handle to forcibly hold the mop in constant sliding contact with the floor surface during the operation of the machine, the operation of said supporting means permitting 100 the brush to lower into engagement with 105 the floor.

8. In a machine of the character described, a wheel supported shaft, a frame loosely engaged at its rear end upon said shaft, an endless traveling mop vertically 110 movable in the forward end of said frame, friction drive wheels for said traveling mop mounted in the frame and supporting the same, a roller upon which the mop is engaged, friction wheels upon opposite ends 115 of the roller shaft, means to yieldingly hold the lower stretch of the mop in constant sliding engagement with the floor surface during the operation of the machine and maintain said friction wheels in operative 120 engagement with the frame supporting wheels, said means including means to elevate the mop in the frame out of operative 125 relation to the drive wheels.

9. In a machine of the character described, a wheel supported frame, an endless traveling mop vertically movable in said frame and including supporting rollers, friction wheels arranged at opposite ends of 130 one of the supporting rollers to positively 130

rotate the same, means to yieldingly hold the lower stretch of the traveling mop in constant sliding contact with the floor surface as the machine is propelled and also hold said friction wheels in operative engagement with the frame supporting wheels whereby the mop roller is positively rotated, said means including means operable to elevate the mop in the frame out of contact with the floor surface and support the same in an inoperative position with relation to the frame supporting wheels.

10. In a machine of the character described, a wheel supported shaft, a main frame mounted upon said shaft, supporting wheels mounted in the forward end of the frame, a mop frame, an endless traveling mop mounted therein, means to removably and pivotally support the mop frame upon said main frame, means to yieldingly hold the mop frame against pivotal movement and maintain the lower stretch of the mop in constant sliding contact with the floor surface as the machine is propelled over the floor, friction wheels to positively actuate the mop, said last referred to means also operating to maintain said wheels in frictional engagement with the frame supporting wheels, said means including a movable handle whereby the machine is propelled, and means connected to said handle and operated thereby in its movement in one direction to move the mop frame with relation to the main frame and elevate the lower stretch of the mop out of contact with the floor surface.

11. In a machine of the character described, a wheel supported shaft, frame bars mounted at one of their ends upon said shaft, frame plates secured upon the other ends of said bars, floor engaging wheels supporting the latter ends of the bars, a mop including spaced frame members each provided with a stud adapted to be removably mounted in one of the frame plates for rocking movement, a roller journaled at its ends in said members, a tensioning roller mounted upon said members, an endless mop web traversing said rollers, friction wheels at opposite ends of the first named roller, means yieldingly holding the lower stretch of the web in engagement with the floor surface and said friction wheels in contact with the peripheries of the frame supporting wheels, said holding means including a pair of levers fulcrumed intermediate of their ends, movably mounted bars provided upon their forward ends with rollers for engagement with the mop frame, said rollers being adapted to rock the mop frame upon said frame plates and elevate the lower stretch of the mop out of contact with the floor surface and also move said latter levers to release the holding means.

12. In a machine of the character de-

scribed, a wheel supported shaft, a tank mounted upon said shaft, a forwardly extending frame mounted upon the shaft, an endless traveling mop vertically movable in said frame, means to yieldingly hold the lower stretch of the mop in sliding contact with the floor surface during the movement of the machine, means for positively actuating the mop, means for compressing the mop web to extract the water therefrom, a movable handle, and means actuated by the movement of the handle in one direction to destroy the function of said holding means and elevate the mop to an inoperative position in the main frame out of contact with the floor surface.

13. In a machine of the character described, a wheel supported main frame, a mop frame fulcrumed at its rear end upon said main frame, an endless traveling mop mounted in said mop frame, a pivotally mounted element connected at one of its ends to the rear pivoted end of the mop frame, a manually operable member engaged with the frame at its pivoted end and adapted, when moved in one direction, to elevate said frame and dispose the mop out of engagement with the floor, said member when moved in the opposite direction, co-operating with said pivoted element at its free end to cause the same to exert a positive downward pull upon the mop frame and forcibly hold the mop in contact with the floor surface.

14. In a machine of the character described, a frame consisting of similar side plates, a roller journaled at its ends in said side plates, a tensioning roller mounted upon said side plates, an endless mop web extending around said rollers, a presser roller arranged between the side plates and bearing upon the upper stretch of the web contiguous to the periphery of said first named roller, said presser roller being provided with trunnions upon its ends, bearing arms slidably mounted in said plates and engaging the roller trunnions, housings, studs projecting from said housings, said frame plates being provided with slots to accommodate said studs, bolts loosely mounted in said bearing arms and extending through the housings, springs arranged in the housings upon said bolts and acting to yieldingly hold the bearing arms against movement with relation to the housings, and means mounted upon the frame plates and connected to said studs to lock the housings and bearing arms against movement with respect to the plates.

15. In a machine of the character described, a mop frame fulcrumed at one of its ends for rocking movement, an endless traveling mop mounted in the frame, a bar pivotally mounted intermediate of its ends, a handle mounted upon one end of said bar, the other end of said bar engaging the mop

- frame whereby when the handle is moved in one direction the frame is swung upwardly from its fulcrum and the mop held out of engagement with the floor surface, and a 5 movable element yieldably connected to said frame and actuated by said pivoted bar when the handle is moved in the opposite direction to yieldably hold the mop in engagement with the floor surface.
- 10 16. In a machine of the character described, a frame consisting of spaced plates, a roller journaled at its ends in said plates, a second roller mounted upon the frame plates, an endless mop web arranged upon 15 said rollers, a presser roller arranged between said plates and adapted to compress the mop web upon the periphery of the first named roller, bearing members slidably mounted upon the respective frame plates 20 and engaging the ends of the presser roller, additional members also slidably mounted upon said plates, means yieldingly holding the bearing members against movement with respect to said latter members, and means 25 mounted upon each of the frame plates and connected to said latter members to slide the same together with the bearing members and dispose the bearing members out of bearing engagement with the ends of the 30 presser roller.
17. In a machine of the character described, a frame consisting of spaced plates, a roller journaled at its ends in said plates, a second roller mounted upon the frame 35 plates, an endless mop web arranged upon said rollers, a presser roller arranged between the frame plates to compress the mop web upon the periphery of the first named roller, housings slidably mounted upon the 40 respective frame plates, bearing arms slideable upon the frame plates with respect to said housings, bolts adjustable in said arms and extending through the housings, springs arranged in the housings upon said bolts to 45 yieldingly hold the bearing members against movement with respect to the housings, a manually operable lever pivotally mounted at one of its ends upon each of the frame plates, and links connecting said levers to 50 the respective housings whereby the same and the bearing arms are moved upon the frame plates to lock the arms in yielding engagement with the ends of the presser roller or disengage the arms from the roller 55 to admit of the removal of said roller.
18. In a machine of the character described, a shaft, a wheel revolvably mounted upon said shaft, a horizontally disposed U-shaped bar mounted to oscillate upon said 60 shaft, forwardly and downwardly extending frame bars mounted at their rear ends upon the shaft, supporting wheels for the forward ends of said frame bars, an endless traveling mop fulcrumed for bodily vertical movement upon the forward ends of said 65 frame bars, rotary brushes mounted in advance of said mop and supported by the frame bars for vertical swinging movement with respect to the mop, operating means for said brushes including a rod engaged with said U-shaped bar, bars pivotally mounted intermediate of their ends, a handle connected to the rear ends of said bars and to said U-shaped bar, said handle in its movement in one direction causing the U-shaped bar to exert an upward pressure upon said rod and thereby elevating the brushes out of contact with the floor surface, said pivoted bars being simultaneously moved and their forward ends engaging 70 with the mop to lift the same out of contact with the floor surface.
19. In a machine of the character described, a shaft, a wheel revolvably mounted upon said shaft, a U-shaped bar mounted to 75 oscillate upon said shaft, a frame mounted at its rear end on the shaft, forwardly extending bars pivotally mounted upon said frame for vertical swinging movement, a rotary brush mounted upon the forward end 80 of each of said latter bars, means for operating said brushes including a connecting rod extending above the intermediate portion of said U-shaped bar, a handle connected to said bar to oscillate the same upon the 85 shaft and elevate the brushes upon said frame bars out of engagement with the floor surface, and means for engagement by said connecting rod to support the brushes when the same are swung upwardly upon the 90 frame bars to a substantially vertical position.
20. In a machine of the character described, a shaft, a wheel revolvably mounted upon said shaft, a frame loosely mounted 95 at its rear end upon the shaft, said frame including forwardly extending parallel bars, a rotary brush mounted upon the forward end of each of said bars, a supporting member connecting said frame bars and 100 longitudinally adjustable thereon, a slide block mounted upon said member, means actuated from the supporting wheel for reciprocating said slide block, links pivotally connected at one of their ends to the block 105 and extending in relatively opposite directions therefrom, the other ends of said links being pivotally mounted upon the supporting member, additional links slidable upon the first named links and movable therewith 110 in their pivotal movement, and levers connecting the latter links with the respective brushes to impart a rotary oscillating movement to said brushes.
21. In a machine of the character described, a shaft, a supporting wheel loosely mounted upon said shaft, a frame loosely 115 engaged at its rear end upon the shaft and

including forwardly extending parallel frame bars, a rotary brush mounted upon the forward end of each of said bars, each of said brushes being provided with a plurality of radial arms adapted for interfitting engagement with the arms of the other brush when said brushes are rotated, a supporting member connecting said frame bars, an adjustably mounted spring-pressed 5 caster wheel arranged upon the under side of the supporting member, a slide block mounted upon said supporting member, means actuated from the main supporting wheel for reciprocating said slide block, and 10 connections between each of the brushes and said slide block to impart a rotary oscillating movement to the brushes as the machine is propelled over the floor.

22. In a machine of the character described, a mop frame fulcrumed at one of its ends, an endless mop mounted in said frame, means for operating the mop, a pivotally mounted handle whereby the machine is propelled, and means carried by said handle 20 to engage and rock the mop frame upon its fulcrum and elevate the mop out of contact with the floor surface.

23. In a machine of the character described, a mop frame fulcrumed at one of its 25 ends, a drive roller mounted in said frame, a forward longitudinally movable roller mounted in said frame, an endless mop adapted to be inserted over the frame and engaged upon said rollers, means for limiting the downward movement of the forward 30 roller with respect to the frame, means to rock said frame upon its fulcrum and positively engage the lower stretch of the mop with the floor, and means for cushioning the upward vertical movement of the 35 forward roller with respect to said frame, said roller creating an additional yielding pressure of the mop upon the floor surface.

24. In a machine of the character described, a mop frame fulcrumed at one of its ends, a rear driving roller mounted in said 40 frame, a forward roller longitudinally movable in the frame, an endless mop adapted to be inserted over said frame and engaged 45 upon the rollers, said forward roller being moved inwardly to permit of the engagement of the mop thereon, said forward roller being also mounted for vertical bodily movement with respect to the frame, 50 springs acting to force the roller downwardly, stops to limit such downward movement, a manually operable member co-operating with the frame to elevate the same and hold the mop out of engagement with 55 the floor, and additional means connected to the mop frame and actuated by said member to effect a positive pressure of the mop upon the floor surface, said spring pressed forward roller exerting an independent 60

downward pressure upon the forward end 65 of the mop.

25. In a machine of the character described, a vertically movable mop frame, a driving roller mounted in said frame, means for operating said roller, supports pivotally 70 mounted upon the frame, a forward roller arranged upon said supports, a mop adapted to be arranged upon said rollers, means yieldingly acting to force the roller supports downwardly, stops to limit such movement of the supports, and means for elevating said frame to disengage the mop from the floor surface and move the drive roller out of co-operative relation with said operating means.

26. In a machine of the character described, a vertically movable mop frame, a driving roller mounted in said frame, means for operating said roller, supports pivotally 75 mounted upon the frame, a forward roller arranged upon said supports, a mop adapted to be arranged upon said rollers, said means for elevating said frame to disengage the mop from the floor surface and move the drive roller out of co-operative relation with 80 said operating means, and means for preventing pivotal movement of the forward roller support in a direction to engage the mop with the floor when the same is elevated.

27. In a machine of the character described, a wheel supported main frame, a brush frame loosely mounted upon the main frame and extending forwardly thereof, rotary brushes mounted upon the latter frame, 100 means operated from the supporting wheel for actuating said brushes including a connecting rod, means for detachably engaging said rod at one of its ends with said operating means whereby the brush frame 105 may be swung upwardly and the brushes disposed in an inoperative position, and means to which said rod is adapted to be connected to support the brush frame in the latter position.

28. In a machine of the character described, a wheel supported main frame, a brush frame loosely mounted upon the main frame for vertical swinging movement and extending forwardly thereof, a rotary brush 110 mounted upon the brush frame, means for actuating said brush including a crank, gearing driven from the supporting wheel to actuate said crank, a pivot stud secured to the crank, an arm secured to the axis of the rotary brush, a connecting rod, operating connections between one end of said rod and said arm, a hook formed on the other end of said rod for detachable engagement with said pivot stud, a water supply tank 120 carried by the machine, said connecting rod being adapted to be disengaged from the stud on the crank arm whereby the brush 125

frame may be swung to a vertical position with respect to the main frame, and a rod fixed to the water supply tank with which the hook on the connecting rod is adapted to be engaged to support the brush frame in the latter position.

In testimony whereof I hereunto affix my signature in the presence of two witnesses.

HARRY F. JOSEPH.
